(57) CLAIM

The ornamental design for a toy makeup case, as shown and described.

DESCRIPTION

FIG. 1 is a front and top perspective view of a toy makeup case, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in an alternative-position.

The evenly dashed lines are shown for the purpose of illustrating both parts of the toy makeup case as well as environmental subject matter. None of the dashed lines form part of the claimed design.
